PAPER BOX

Sam P. Cohn, San Francisco, Calif.

Application November 21, 1938, Serial No. 241,550

2 Claims. (Cl. 229—52)

This invention relates to paper boxes and it has for its principal object the provision of a paper or cardboard box of the suit box type, having a handle for the convenient carrying of the same.

A further object of the invention is to provide a box of the character mentioned from a one-piece blank and which is set up and folded upon itself to make a complete box, and to provide the box with an attachable handle member.

I am aware of the fact that the prior art contains instances in which others have sought to meet the objectives of this invention but as one experienced in this specific art it has been my observation that each and all of the prior art structures are subject to criticism for one reason or another; not the least of these being the fact that the boxes were unduly complex; difficult to manufacture; required extreme patience in assembling, and lacked the necessary strength.

It has therefore been an object to provide a suit box which could be cheaply manufactured and quickly assembled by even the less experienced.

These and other objects of the invention will become more apparent as this specification proceeds and the novelty thereof will be particularly pointed out in the append claims.

In the drawings forming a part hereof:

Fig. 1 is a plan view of the box blank and handle member.

Fig. 2 is a perspective view of the completely assembled box.

Fig. 3 is a perspective view of the box of Fig. 2 in partly opened condition.

Fig. 4 is a perspective view of the box opened to a greater extent than is shown in Fig. 3 and without the handle member.

Fig. 5 is a fragmentary perspective of the handle section of the box in the first stage of the assembly.

Fig. 6 is a fragmentary perspective of the handle section of the box in the second stage of assembly.

Fig. 7 corresponds to Fig. 6 and shows the next stage of assembly.

Fig. 8 corresponds to Figs. 5 to 7, inclusive, and shows the final stage of assembly.

Fig. 9 is a longitudinal section through the handle section of the box to show the relative position of parts.

Fig. 10 is a perspective view showing the handle member in partly assembled condition, and

Fig. 11 is a perspective view showing the handle as completely folded.

The numeral 10 designates the box blank and a handle member 11 (in full extended condition) is shown in juxtaposition thereto for the purpose of indicating that the two members are cut from a single piece of stock. The position of the handle member 11 in Fig. 1 is illustrative only since it is obvious that it may be cut from that portion of the stock extending beyond any of the margins of the blank 10.

10 The blank 10 is provided with the longitudinally extending scorelines 12 and 15 to define outer and inner front wall sections 16 and 20, respectively. Scorelines 13 and 14, paralleling the lines 12 and 15, define the single backwall section 18 and with the scorelines 12 and 15, the top 17 and the bottom 19.

Scorelines 29 and 30 extending transversely of the box blank 10, define the box end sections 24 and 25, of the top section 17; the notched extensions 28 for the back section 18, and the end sections 26 and 27 of the bottom 19. Additionally, scorelines 29 and 30 define the foldable margins of the tongues 31, at the ends of outer front section 16 and inner front section 20.

25 In assembling the box thus defined, the front sections 16 and 20 are folded along scorelines 12 and 15, respectively, and end sections 24 to 27, inclusive, are folded upwardly along the scorelines 12 and 15, respectively. The front and end sections are then connected by engagement of the conventional tongues 31 with the slits 35 in the end sections.

30 The structure thus formed is foldable upon itself, in the manner illustrated in Fig. 4, notched sections 28 being scored to provide an accordion fold and permitting end sections 24 and 25 to overlap end sections 26 and 27, respectively.

The separate handle 10 is shown to best advantage in Figs. 1, 10, and 11. It comprises a plurality of bit-shaped pieces interconnected at their ends, as cut from a single piece of material, foldable upon themselves to provide the unitary member shown in Fig. 11. This construction is preferred because the handle thus provided is considerably stronger than a single thickness of material and because of the facility with which the handle may be inserted in its proper position, but it will be appreciated that the handle may be divided into separate pieces without departing from the spirit of the invention. The enlarged ends 36 of the shank of the handle 11 are the means of connecting the same to the box as will hereinafter appear.

35 Slits 37 and 38 are provided in the outer and inner front sections 16 and 20, respectively, to

permit interconnection of handle 11 and the box.

The slit 37 comprises U-shaped arrangement of a longitudinally extending slit 39, adjacent the edge of the outer front section, having cut-out slots 40 extending laterally therefrom, and parallel the ends of the section 16. Thus a punch-out bendable tab 41 is defined. The slots 40 facilitate the insertion of the handle as will be made to appear.

The slits 38 in inner front section 20 comprise a pair of slots 42, in registry with slots 40 in front section 16; slits 43 extending at right-angles thereto and parallel to the edges of the section; slits 44 at right-angles to slits 43 and opposite slots 42, and the relatively short slits 45 extending inwardly at right-angles to slits 44. This arrangement provides the bendable tabs 46.

In assembling the structure just described the order is as outlined in Figs. 5 to 8, inclusive. The enlarged ends 36 of the handle 11 are first passed through the slits 42 to 45, inclusive (see Fig. 5), and hooked under front section 20.

The next step is the telescoping of the box top 17 and bottom 19, the condition of the box at the commencement of this step being illustrated in Fig. 3. The tab 41 is bent inwardly and the marginal edge of front section 16 is raised and passed over the handle member 11; tab 41 being passed between the surface of section 20 and handle 11 (see Fig. 7). Further movement causes the handle 11 to enter the slots 40 in front section 16 and the handle is then pulled outwardly into extended position (see Figs. 2 and 8).

While it is true that this interconnection of box and handle provides a locking means which in the majority of cases would serve effectively to keep the box closed, nevertheless auxiliary lock means 48 and 49 is provided. On opposite sides of the slotted area 37 in front section 16, I provide the opposed U-shaped slits 48. T-shaped punch-out tabs 49, in front section 20, are in registry with the slits 48 and in effecting the interlocking of the box members with this means the ends of the cross-bars in the tabs 49 are merely inserted through the opposed slits 48 (see Fig. 2).

It is believed clear that I have provided a box which can be quickly and conveniently assembled, and one which is of extremely simple and inexpensive construction.

The box forming the subject matter of this invention has been particularly devised for use in carrying articles of wearing apparel and as such it is obvious it will serve effectively to support considerable weight. The principle of the invention is, however, by no means limited to suit boxes and it may find many uses in the container art. Moreover the device may be changed to suit varying needs and conditions without departing from the spirit of the invention and for

this reason I deem the form shown in the drawings as illustrative only; not as a limitation.

I claim:

1. In a paper box, the combination of hinged top and bottom sections which when telescoped form a container of the suit box type, a bit-shaped handle member having enlarged ends, a pair of spaced slots transversely disposed in the front section of the box bottom of sufficient size to receive the shank of the handle but smaller than the enlarged ends of the handle, a slit extending longitudinally of the front section of the box bottom and outwardly from the corresponding end of each of said slots, a second slit extending transversely of the front section of the box bottom from the end of each of said longitudinal slits and on the sides thereof opposite to said slots, and a third slit extending longitudinally of the front section of the box bottom from the end of each of the second named slits parallel to the first named slits and inwardly toward the middle of the front section of the box bottom, the said end of said slots from which the slits extend being the end remote from the free edge of the front section of the box bottom.
2. In a paper box, the combination of hinged top and bottom sections which when telescoped form a container of the suit box type, a bit-shaped handle member having enlarged ends, a pair of spaced slots transversely disposed in the front section of the box bottom of sufficient size to receive the shank of the handle but smaller than the enlarged ends of the handle, a slit extending longitudinally of the front section of the box bottom and outwardly from the corresponding end of each of said slots, a second slit extending transversely of the front section of the box bottom from the end of each of said longitudinal slits and on the sides thereof opposite to said slots, a third slit relatively shorter than the two first named slits extending longitudinally of the front section of the box bottom from the end of each of the second slits parallel to the first named slits and inwardly toward the middle of the front section of the box bottom, the said end of said slots from which the slits extend being the end remote from the free edge of the front section of the box bottom, a pair of transversely disposed slots in the front section of the box top adapted to register with the corresponding slots in the front section of the box bottom when the box is in closed condition, and a slit extending longitudinally of the front section of the box top connecting the ends of slots therein adjacent the bottom edge of the front section of the box top to provide a locking tab to retain the handle member in carrying position when the box is in closed relation.

SAM P. COHN.
